[57] **CLAIM**

The ornamental design for a combined vehicle sun visor and removable screen, as shown and described.

DESCRIPTION

FIG. 1 is a perspective view of combined vehicle sun visor and removable screen showing our new design.

FIG. 2 is an enlarged front view of the vehicle sun visor without the screen, shown broken away for ease of illustration;

FIG. 3 is a side view of FIG. 2;

FIG. 4 is an enlarged front view of the screen, shown separately and broken away for ease of illustration; and,

FIG. 5 is a perspective view of the combined vehicle sun visor and screen with the screen in an unrolled position.

The portion of the sun visor and screen not shown in the drawings form no part of the claimed design.
